UNITED STATES PATENT OFFICE.

WILLIAM S. FELL, OF NEW ORLEANS, LOUISIANA.

WINDOW-LATCH.

1,227,768.

Specification of Letters Patent.

Patented May 29, 1917.

Application filed January 27, 1917, Serial No. 144,943.

To all whom it may concern:

Be it known that I, WILLIAM S. FELL, a citizen of the United States, residing at New Orleans, in the parish of Orleans and State of Louisiana, have invented certain new and useful Improvements in Window-Latches, of which the following is a specification, reference being had to the accompanying drawings.

10 This invention relates to windows and particularly to window latches.

The general object of the invention is the provision of a very simple, cheaply made and easily applied window latch which automatically locks the lower sash from being raised and the upper sash from being lowered whenever the two sashes are closed but in which the latching member may be readily shifted to an inoperative position 20 to permit the raising or lowering of the lower or upper sashes respectively.

A further object of the invention is to provide a latching device of this character embodying a pivoted member mounted upon the upper sash and adapted to normally extend over the upper rail of the lower sash and a locking member which is pivotally mounted upon the pivoted member and normally rests against a portion of the upper 30 sash in such manner that if it be attempted to lower the upper sash or raise the lower sash, this locking member will wedge between the upper and lower sashes, preventing any movement of either sash, and in this connection to provide for the pivoted member dropping into position over the meeting rail of the lower sash when the lower sash is shifted to its fully lowered position and the upper sash is lifted to its fully raised 40 position.

Another object is to provide a device of this character which cannot be shifted to an inoperative position by the insertion of an implement between the meeting rails of the sashes.

Other objects will appear in the course of the following description.

My invention is illustrated in the accompanying drawings, wherein,

50 Figure 1 is a face view of a portion of the window frame, a portion of the upper sash and a portion of the lower sash;

Fig. 2 is a section on the line 2-2 of Fig. 1;

55 Fig. 3 is a section on the same plane as

Fig. 2 but showing the lower sash raised with relation to the upper sash;

Fig. 4 is a section on the line 4-4 of Fig. 2;

Fig. 5 is an elevation of a modified form 60 of the tongue 12; and

Fig. 6 is a vertical section through the tongue 12 showing the lateral guard flanges.

Referring to these figures, A designates the upper sash of a window and a the meeting rail thereof. B designates the lower sash of the window and b the meeting rail thereof, C designating the window casing as a whole. It is to be understood that my invention does not relate to any particular 70 construction of window casing or window sashes as the device may be applied to all forms of windows having sliding sashes.

Inserted in a mortise in a vertical rail of the upper sash just above the meeting rail a is a box or casing 10 which is preferably of metal and which is illustrated as held in place in this mortise by means of screws 11 passing through the back wall of the box, though it may be held in place by any other 80 suitable means. Pivotaly mounted on the bottom of the casing 10 is a tongue 12 which is preferably made of metal and which is shown as pivoted upon a transversely extending bolt or pin 13, though other means 85 for pivoting this tongue may be provided. Preferably the tongue is cut away at 14 so as to fit over the box and lie flat upon the meeting rail b. Preferably also the tongue is rounded at its free end as at 15 for a purpose which will later appear. Pivotaly mounted upon the upper face of the tongue 90 is the locking member or wedge 16 which is also formed of a piece of relatively thick metal bifurcated at one end as at 17 to fit 95 over a knuckle 18 formed upon the tongue 12. The free end of this locking member 16 is disposed at an obtuse angle to the upper and lower faces of the member 16 so that when this locking member 16 is in the position shown in Fig. 2, the end of the tongue will fit flat against the rear wall of the casing 10. This locking member 16 is provided 100 with a stud 19 whereby it may be shifted by hand. Any form of stud may be used but I have shown the stud in the form of a screw, so that it may be adjusted or removed entirely for the purpose which will be later stated.

The operation of the device will be ob- 110

vious from the drawings. When the upper and lower sashes are closed and the tongue 12 lies on the face of the meeting rail *b*, then if it be attempted to lift the lower sash, the upward movement of the tongue 12 will jam the locking member 16 against the rear wall of the box 10 and wedge so that no movement of the lower sash can possibly be secured. As a matter of fact, the weight of 10 the member 16 will cause it to drop into wedging position so that there is practically no movement possible for the lower sash. The same thing is true of a downward movement of the upper sash. If it 15 be attempted to move the upper sash downward, the action will be precisely the same as if the lower sash were moved upward and the locking member 16 will wedge in place, holding the two sashes from any relative 20 movement. If it be desired now to raise the lower sash or lower the upper sash, the operator by means of the stud 19 shifts the locking bar, wedge or tongue 16 over to the position shown in dotted lines in Fig. 2, 25 whereupon the upper sash may be lowered or the lower sash raised. As the lower sash is raised, however, relative to the upper sash, the tongue 12 will be raised, as shown in Fig. 3, and the locking bar 16 will be 30 thrown over to the position shown in Fig. 3, resting against the rear face of the casing 10. This is a position of unstable equilibrium and as soon as the lower sash is lowered beyond the tongue 12, the tongue will 35 drop back again to the position shown in Fig. 2 and the wedge or locking member 16 will drop back to the position shown in Fig. 2, locking the two sashes from any relative movement. Of course, the like operation 40 will occur upon a lowering of the upper sash. It will be seen that the rounded end 15 of the tongue 12 will cause it to ride smoothly along the inside face of the meeting rail *b* so that there will be no chance of 45 its wedging or jamming when the lower sash is moved relatively downward.

While I have illustrated this device as applied to windows, it will be obvious that it may be applied in other situations where 50 it is desired to lock two members from relative movement and it will also be seen that the device may not only be applied to ordinary windows but is particularly applicable to the windows of storehouses, garages, 55 barns and general farm windows. It will also be noted that it is impossible to open this lock by the insertion of an implement between the meeting rails of the sashes. The ordinary window latch which has a locking member pivoted to the meeting rail of 60 the upper sash and movable in a horizontal plane across the meeting rail of the lower sash is capable of being opened by the insertion of a blade or other implement between these meeting rails, said implement 65

being used to exert a lateral pressure upon the locking member which will turn it in a horizontal plane; but this is impossible with this construction as a lateral pressure on the tongue 12 will of course not affect the 70 lock in any way and an upper pressure on the tongue would simply act in the same manner as if upward pressure was applied upon the lower sash.

It might be possible, with the construction shown in Figs. 1 and 2, to insert an implement with a hook shaped end between the meeting rails of the sashes *a* and *b* and then work the hook shaped ends into position beneath the wedge 16 and then raise the 75 wedge. In order to prevent this I may make the tongue in the manner shown in Figs. 5 and 6 wherein the tongue 12^a is shown as being provided with the upwardly projecting, longitudinally extending flanges 80 20, which extend high enough to guard or shield the spaces between the tongue and the wedge and thus prevent the insertion of any member beneath the wedge.

It will be noted from Fig. 3 that the stud 90 19 prevents the tongue 12 from being turned to a vertical position or beyond a vertical position so that when the lower sash is lifted, the tongue cannot be turned beyond its center and thus when the lower sash is 95 lowered, the tongue will automatically fall to its locking position, that is the position shown in Fig. 2.

It is to be noted that if this screw 19 be removed or suitably adjusted the tongue and 100 locking member may be turned up so that the tongue will be disposed in a position inclined toward the rear wall of the casing 10 and thus will be held in an inoperative position. By adjusting the stud 19, however, it is possible to limit the inward movement of the tongue 12 to such a position that the free end of the tongue cannot be forced inward beyond a certain point so that the 105 tongue will be supported until it is, when 110 in a raised position, in a plane upwardly and outwardly inclined so that as soon as the lower sash has been relatively shifted, below the upper end of the tongue, the 115 tongue will commence to move outward and downward and will eventually reach the position shown in Fig. 2.

Having described my invention, what I claim is:

1. A sash fastener comprising a casing 120 having a tongue pivoted within and at the bottom of the casing and normally disposed in a horizontal plane and projecting out of the casing, but movable in a vertical plane to a position within the casing, and a locking member hingedly mounted on the upper 125 face of the tongue and urging the tongue by gravity to a horizontal position, said locking member when the tongue is in a horizontal position being upwardly and rearwardly in- 130

clined and bearing against the rear face of the casing, there being means for preventing the outer end of the tongue from being moved inward to a vertical plane intersecting the pivotal center of the tongue to thereby cause the tongue to be constantly urged by gravity to a horizontal position.

2. The combination with the upper and lower sashes of a window, said sashes having meeting rails, of a supporting member mounted upon the upper sash adjacent the upper face of the meeting rail of that sash, a tongue hingedly connected to the supporting member and normally lying in a horizontal plane over the upper face of the meeting rail of the lower sash, and a locking member hingedly connected to the upper face of the tongue intermediate the ends of the tongue, said locking member extending rearward and bearing against the confronting face of the supporting member, the weight of the locking member urging the tongue to its horizontal position and urging the free end of the locking member into wedging engagement with the supporting member, there being means for preventing the free end of the tongue from moving inward to a position beyond a vertical plane intersecting the pivotal axis of the tongue.

3. A sash fastener comprising a casing, a tongue pivoted adjacent the lower end of the casing and inward of the forward edge of the bottom of the casing and normally lying in a horizontal plane and projected from the casing, but movable in a vertical plane to a position within the casing, a locking member hingedly mounted upon the upper face of the tongue, said locking member when the tongue is in a horizontal position being upwardly and rearwardly inclined and bearing against the rear face of the casing, the end of the locking member being beveled to engage flat against said rear end of the casing and the weight of the tongue urging the tongue to its horizontal position and causing the beveled end of the tongue to have wedging engagement with the rear face of the casing, the locking member having its inner end hinged to the lower end of the casing at a point sufficiently inward from the outer edge of the casing that the tongue when raised has its outer face within the plane of the outer edge of the casing and is disposed in an upwardly and outwardly inclined position, whereby the tongue is constantly urged to a horizontal position by its weight, and means for preventing the outer end of the tongue from moving inward to a position to or beyond a vertical plane intersecting the pivotal axis of the tongue.

4. The combination with an upper sash and a lower sash having meeting rails, of a rectangular casing disposed within one of the rails of the upper sash and resting upon the meeting rail thereof, a tongue pivoted

at its rear end to the bottom of said casing, inward of the forward edge of the casing and normally disposed in a horizontal position over the upper face of the meeting rail of the lower sash, a locking member hinged to the upper face of the tongue intermediate the ends of the tongue and said locking member when the tongue is in a horizontal position extending rearward and slightly upward and bearing against the rear wall of the casing, the end of the locking member being beveled to bear flat against said rear wall, said locking member at all times urging said tongue to a horizontal position and the end of the locking member having wedging engagement with the rear wall of the casing when the tongue is in a horizontal position, and a stud on the locking member whereby it may be manually lifted from its locking position, said stud preventing the tongue from being shifted so far into the casing as to prevent the dropping of the tongue to its horizontal position by gravity.

5. A sash fastener comprising a supporting member having a tongue pivoted to it, and normally disposed in horizontal plane and adapted to overlie the lower sash of a window, said tongue being movable in a vertical plane to an approximately vertical position, and a locking member hingedly mounted on the outward face of the tongue intermediate of its ends and urging the tongue by gravity to a horizontal position, said locking member when the tongue is in a horizontal position being upwardly and rearwardly inclined and bearing against said supporting member, the tongue being formed with upwardly extending parallel guard flanges on each side of the locking member, preventing the insertion of an implement beneath the locking member.

6. A sash fastener comprising a supporting member, a tongue pivoted to the lower end of the supporting member and normally disposed in a horizontal plane but movable in a vertical plane toward the supporting member, a locking member hingedly connected to the tongue, said locking member when the tongue is in a horizontal position being upwardly and rearwardly inclined and bearing against the supporting member and having wedging engagement therewith, and means for preventing the outer end of the tongue from moving upward and toward the supporting member to a position with its free end beyond a vertical plane intersecting the pivotal axis of the tongue, said means being movable out of operative position to permit the tongue to be shifted to a position with its free end inward of said plane.

7. A sash fastener comprising a casing having an inner face extending in one plane for its entire length, a tongue pivoted with

in and at the bottom of the casing, the tongue being shorter than the length of the casing and normally disposed in a horizontal plane and projecting out of the casing but movable in a vertical plane to a position within the casing, a locking member hingedly mounted on the upper face of the tongue intermediate of its ends, the distance from the pivotal axis of the tongue to the extremity of the locking member when the tongue and locking member are in approximately parallel relation being less than the length of the casing, the locking member when the tongue is in a horizontal position being upwardly and rearwardly inclined and bearing against the rear face of the casing and having wedging engagement therewith, and means for preventing the inward movement of the free end of the tongue to a position beyond a vertical plane intersecting the pivotal axis of the tongue.

8. A sash fastener comprising a vertical support, a tongue pivoted to said support and movable outwardly therefrom to a horizontal position, a locking member pivoted to said tongue and movable into a backwardly and upwardly inclined position relative to the tongue and at an obtuse angle thereto and into wedging engagement with the face of said support, and movable means, in one position preventing the tongue from being raised to a position where its free end is inward of a vertical plane intersecting the axis of the tongue, said means when out of said position permitting the tongue to be so raised.

In testimony whereof I hereunto affix my signature in the presence of two witnesses.

WILLIAM S. FELL.
